UNITED STATES PATENT OFFICE.

WILLIAM C. WRIGHT, OF AMSTERDAM, NEW YORK.

DESIGN FOR A CARD-RECEIVER.

SPECIFICATION forming part of Design No. 17,761, dated October 4, 1887.

Application filed July 13, 1887. Serial No. 244,207. Term of patent 3½ years.

To all whom it may concern:

Be it known that I, WILLIAM C. WRIGHT, a citizen of the United States, residing at Amsterdam, in the county of Montgomery, State of New York, have invented certain new and original Designs for Card-Receipters, of which the following is a specification, reference being had therein to the accompanying drawing.

Referring to the drawing, which is a perspective of my design for card-receiver, A represents the receiver, which is of a canoe or boat shape, and is provided with the opening A' in its deck A². A paddle, B, is secured within the hull, one end projecting therefrom. An ornamentation of a serpentine binding, A³, gives an attractive and tasty appearance. The

canoe or boat has a base, C, which consists of the legs C' at each end crossed and connected by a rod, C².

What I claim is—

The design for card-receivers, the same consisting of a canoe or boat like configuration, the edges of which terminate in a serpentine coil, and provided with a base and with a part of an oar or paddle, substantially as herein shown and described.

In testimony whereof I affix my signature in presence of two witnesses.

WILLIAM C. WRIGHT.

Witnesses:

ADAM REITZ,
JOHN WRIGHT.
